CLAIM

The ornamental design of an ice pack as shown and described.

DESCRIPTION

FIG. 1 is a perspective view of an ice pack embodying the design of the present invention;

FIG. 2 is a bottom perspective view of the ice pack illustrated in FIG. 1;

FIG. 3 is a back side view of the ice pack illustrated in FIG. 1;

FIG. 4 is a front side view of the ice pack illustrated in FIG. 1;

FIG. 5 is a right side view of the ice pack illustrated in FIG. 1;

FIG. 6 is a left side view of the ice pack illustrated in FIG. 1;

FIG. 7 is a top view of the ice pack illustrated in FIG. 1; and,

FIG. 8 is a bottom view of the ice pack illustrated in FIG. 1.
